UNITED STATES PATENT OFFICE.

CHARLES B. TELLING, OF CLEVELAND, OHIO.

ICE-CREAM-BRICK CONTAINER.

Application filed February 3, 1923. Serial No. 616,710.

As is well known, the manner in which so-called brick ice cream is handled in the ordinary retail establishment is to place the same in a separate refrigerator cabinet wherein is provided a chamber about which ice is packed, the bricks being piled in said chamber one above the other, whether the chamber opens from above or one side. It is unnecessary to recite the numerous objections that attend this method of handling the product in question other than to note that the icing of a separate refrigerator is necessarily expensive and that the product is not readily accessible, it being frequently necessary to remove the entire contents of the cabinet in order to get at the particular brick wanted. Furthermore, if the cabinet be not kept tightly closed, the product is apt to soften and rapidly deteriorate.

The object of the present invention is to provide a form of container that may be installed in the same cabinet wherein the cans of bulk ice cream are placed, such cabinet being usually associated with a dispensing counter, such as is familiarly found in drug stores and the like. The amount of additional refrigeration required will be very small and in addition the construction of the present container is such that all of the stock on hand is readily accessible, while such stock may be readily replaced and the closing of the container cannot well be overlooked. To the accomplishment of the foregoing and related ends, said invention, then consists of the means hereinafter fully described and particularly pointed out in the claim, the annexed drawing and the following description setting forth in detail certain mechanism embodying the invention, such disclosed means constituting, however, but one of various mechanical forms in which the principle of the invention may be used.

In said annexed drawing:—

Fig. 1 is a transverse section through a refrigerating cabinet of the kind referred to above as being associated with a dispensing counter, the container embodying my present improved construction being shown (likewise in section) as installed in said cabinet; Fig. 2 is a perspective view of one element of such container; Fig. 3 is a transverse section through the container in its assembled condition as shown in Fig. 1, but on a somewhat larger scale, the plane of the section being indicated by the line 3—3,

Fig. 1; and Figs. 4 and 5 are detail sections of two modifications.

The detail construction of the refrigerating cabinet 1, shown in Fig. 1, is not of present interest, forming no part of the invention in hand. Ordinarily such cabinet consists of a refrigerating chamber 2, suitably enclosed by heat insulating walls and with a pivotal or otherwise movable cover 3 that when raised permits access to such chamber. The latter is of sufficient length to receive a number of ice cream cans disposed in longitudinally spaced relation and the present container will simply take the place of one such can and will be surrounded, like the latter, with a suitable refrigerant adapted to maintain the contents of the container at the proper low temperature.

The body 5 of the present container consists in effect of a can of rectangular cross-section (see Figs. 1 and 3) of such height as to bring its top just below the cover or lid 3 so that upon raising the latter, the handled cover 6 of said can is in easy reach. Fixedly attached to the under side of such cover 6 is a series of trays 7 that are of rectangular form and of such dimensions as to receive a definite number of ice cream bricks when placed side by side thereon. The trays or shelves 7 are preferably provided with flanges 8 on each side and the rear thereof and they are furthermore provided with perforations 9 so that the bricks may be exposed on their under side, as well as laterally and above, to the refrigerant atmosphere within the can when the latter is properly cooled. The trays or shelves are conveniently attached to the cover 6 by being riveted or otherwise firmly attached to vertically depending bars 10, one at each corner, the vertical spacing of the trays being such as to allow for a slight clearance between the bricks resting on one tray and the under surface of the tray next above, or that of the cover 6, as the case may be.

It will be understood that the dimensions of the trays, as well as the number thereof and the distance the same are spaced apart, will all depend upon the standard size of the bricks and the capacity of the container. It will furthermore be noted that the trays are somewhat smaller than the interior cross-sectional area of the can so as to allow for the free circulation of air entirely about said trays even when completely filled; also that the lowermost tray is supported clear

of the bottom of the can for the same reason and in order that the bricks resting thereon may be kept out of contact with any condensed moisture or water that may collect in the bottom of the can.

In use, assuming the trays or shelves to be properly stocked, when it is desired to take out a brick of a particular character, e. g. flavor, the lid 6 is lifted so as to expose 10 temporarily the entire stock, the desired brick is selected and removed from whatever shelf it may be resting on, and the series of trays dropped back again into the can until the cover rests on the top of the latter. 15 The can is thus necessarily sealed again and the contents exposed for a minimum time. The lids with attached trays are made interchangeable so that it is unnecessary to take out the can when it is desired to re-stock, but 20 a freshly filled set of trays is simply installed for the empty one; or should there be several bricks still left, these are readily transferred to the substitute set of trays wherein the upper trays or shelves will be left vacant 25 for the purpose. This will prevent accumulation of old stock since bricks will naturally be selected from the uppermost shelves first in dispensing the product. The use of racks of my improved design for re-stocking 30 has the further advantage that delivery from truck or wagon to store involves no unnecessary handling of the bricks or exposure thereof; furthermore, the amount of ice cream or number of bricks may be instantly 35 ascertained and the delivery of the product correspondingly speeded up. Finally, there is a very material saving in the amount of refrigeration required over having to ice a

separate cabinet, quite aside from the other annoyances involved in the use of such cabinet for the storage and dispensing of brick ice cream. 40

Instead of relying on the cover to sustain the lowermost tray clear of the bottom of the container, the bars 10 may be carried 45 a corresponding distance below such tray so as to form short legs 11 (see Fig. 4) that serve thus to support the assembled series of trays and so relieve the cover from any suspended load except when it is lifted. In 50 place of such legs 11 projecting downwardly from the tray, lugs or blocks 12 of equivalent height may rise from the bottom of the can as shown in Fig. 5.

Other modes of applying the principle of 55 my invention may be employed instead of the one explained, change being made as regards the mechanism herein disclosed, provided the means stated by the claim or the equivalent of such stated means be employed. 60

I therefore particularly point out and distinctly claim as my invention:—

A bodily transportable unit for brick ice cream and the like comprising a container, a lid having a handle on its upper side and a 65 rack of trays underneath, and means for maintaining the lowermost of the said trays clear of any liquid cream on the bottom of said container, said means comprising brackets on the container a short distance from 70 the bottom thereof upon which the rack is supported.

Signed by me this 31st day of January, 1923.

CHARLES B. TELLING.
